DESIGN FOR AN EMBROIDERED TEXTILE FABRIC OR THE LIKE

William G. Meier, Mamaroneck, N. Y.

Application November 7, 1935, Serial No. 59,432

Term of patent 3½ years

To all whom it may concern:

Be it known that I, William G. Meier, a citizen of the United States, residing at Mamaroneck, New York, have invented a new, original, and ornamental Design for an Embroidered Textile Fabric or the like, of which the following is a specification, reference being had to the accompanying drawing, forming a part hereof.

The figure is a plan view of an embroidered textile fabric showing my new design.

I claim:

The ornamental design for an embroidered textile fabric or the like as shown.

In testimony whereof I have signed this specification.

WILLIAM G. MEIER.
